CLAIM

The ornamental design for a table, as shown and described.

DESCRIPTION

FIG. 1 is a top, rear, and left side perspective view of a first embodiment of a table with a glide;

FIG. 2 is a bottom, rear, and right side perspective view thereof;

FIG. 3 is a front elevational view thereof, the rear elevational view being identical;

FIG. 4 is a right-side elevational view thereof, the left-side elevational view being identical;

FIG. 5 is a top plan view thereof;

FIG. 6 is a bottom plan view thereof

FIG. 7 is a top, rear, and left side perspective view of a second embodiment of the table with a glide;

FIG. 8 is a bottom, rear, and right side perspective view thereof;

FIG. 9 is a front elevational view thereof, the rear elevational view being identical;

FIG. 10 is a right-side elevational view thereof, the left-side elevational view being identical;

FIG. 11 is a top plan view thereof; and,

FIG. 12 is a bottom plan view thereof.

The broken lines depict portions of the article that form no part of the claimed design.

1 Claim, 12 Drawing Sheets
